UNITED STATES PATENT OFFICE.

GEORGE ALLEN REYNOLDS, JR., OF BINGHAMTON, NEW YORK.

NOISELESS WINDOW GUIDE.

Application filed June 16, 1922. Serial No. 568,736.

To all whom it may concern:

Be it known that I, GEORGE A. REYNOLDS, Jr., a citizen of the United States of America, and a resident of Binghamton, in the county of Broome, in the State of New York, have invented new and useful Improvements in a Noiseless Window Guide, of which the following, taken in connection with the accompanying drawings, is a full, clear, and exact description.

This invention relates to a noiseless window guide for sliding window glass as used more particularly in the doors and panels of closed automobiles and analogous purposes.

These guides are preferably made of firm, heavy felt channeled longitudinally along one side and its longitudinal edges folded in the same direction to form a U-shaped guide-strip adapted to be inserted in a suitable groove in the door or window frame for receiving the opposite upright edges of the window glass and guiding the same in its vertical movement, the main object being to provide a cushioned window guide which is practically noiseless and reduces the liability of breakage of the glass.

Heretofore so far as I am aware, these guide strips have been shipped to the users or manufacturers in flat channeled form to be subsequently bent U-shaped in cross-section and stitched along the bending lines to retain the desired cross-sectional contour.

This stitching operation is necessarily painstaking and laborious and therefore time consuming and expensive, and the specific object of my invention is to enable the flat channeled strips to be shipped to the user in compact flat or rolled condition and to provide means whereby the flat strips may be bent into the desired cross-section and retained in that position solely by the bending operation, thereby avoiding the necessity for stitching.

Other objects will be brought out in the following description:

In the drawings:

Figure 1 is a perspective view of a portion of one of the felt strips adapted to form the desired window guide equipped with my improved form retainers but in flat condition before bending.

Figure 2 is a longitudinal section flatwise through a portion of the same strip showing the bendable reinforcing wires therein.

Figure 3 is a transverse sectional view of

the same strip bent to the desired U-shaped form.

Figure 4 is an end view of the guide strip after bending.

As illustrated, this device consists of a strip —1— of firm relatively thick felt of suitable length and width to form the desired window guide and is preferably of uniform width throughout its length and provided with a central lengthwise channel of somewhat greater width than the guide groove which the strip is to form when folded or bent to receive the glass, the portions of the strip adjacent the opposite longitudinal edges of the channel being scored by V-shaped grooves —3— to permit the opposite edges of the strip to be more easily folded along the score-lines.

By channeling the strip along one side necessarily makes the central portion somewhat thinner than that of the opposite edges but nevertheless sufficient thickness for the insertion therethrough of a series of transverse bendable wires —4— so that they will be entirely concealed within the felt when the strip is bent for use as a window guide.

In other words, these bendable wires are inserted transversely through the flat strip from edge to edge thereof and preferably in uniformly spaced relation longitudinally between the inner and outer faces of the thinner portion of the strip and also between the inner and outer faces of the thicker portion of the edges or side walls of the channel.

The ends of the wires are usually sheared off substantially flush with the opposite edges of the strip before bending so that when the opposite edges are bent in the same direction along the grooves or score-lines —3— at substantially right angles to the thinner central portion, they will be in spaced relation transversely to form the desired intervening window-receiving guide groove.

During this bending operation, the ends of the wire will be drawn slightly inwardly from the edges of the felt strip and owing to the nature of the felt, the openings formed by the insertion of the wire in the edges thereof will be automatically closed over the ends of the wire to protect the same from exposure so that each of the wires will be practically concealed within the felt while the combined wires serve not

only to retain the folded strip in its folded position without other retaining means but also serve to reinforce the felt and thereby to add to its durability and strength.

- 5 After the felt strips with the form-retaining wires therein have been bent to the desired form and cut to the required length, they may be readily inserted and secured in place in the grooves of the window or door frame provided therefor to receive and guide the window glass in its vertical movement with the additional advantage of preventing rattle and protecting the glass against breakage. When the wires —4—
10 are bent in the manner shown in Figures 3 and 4, they constitute metal staples for retaining the cross-sectional form of the felt guide and if desired, may be driven from the back into the sides of the felt after the
15 latter has been bent to the desired U-shaped form.

What I claim is:

In a noiseless window guide, an elongated strip of felt having transversely spaced lengthwise grooves in one side between its opposite longitudinal edges, said felt strip having incorporated therein bendable wires extending transversely of and beyond the grooves in longitudinally spaced relation, the opposite longitudinal edges of the strip with the wire therein being folded in one and the same direction along said grooves, the bendable wires serving to hold the longitudinal edges in their folded positions.

30 In witness whereof I have hereunto set my hand this 12th day of June, 1922.

GEORGE ALLEN REYNOLDS, JR.
